[57] CLAIM

The ornamental design for a telescope cradle, as shown and described.

DESCRIPTION

FIG. 1 is a right-hand side elevation of a telescope cradle showing our new design;
 FIG. 2 is a top plan view thereof;
 FIG. 3 is a bottom plan view thereof;
 FIG. 4 is a rear elevation thereof;
 FIG. 5 is a front elevation thereof; and
 FIG. 6 is a right-hand side elevation thereof showing the relation of the cradle to a telescope and mount, the latter elements being shown in broken lines to denote environmental structure only.

FIG. 2.

FIG. 4.

FIG. 1.

FIG. 5.

FIG. 3.

FIG. 6.
